The ornamental design for a reagent card, as shown and described.

DESCRIPTION

FIG. 1 is a top perspective view of a reagent card, showing a first embodiment of my new design;

FIG. 2 is a top view thereof;

FIG. 3 is a front view thereof;

FIG. 4 is a side view, the opposite side being a mirror image thereof;

FIG. 5 is a top perspective view of a reagent card, showing a second embodiment of my new design;

FIG. 6 is a top view thereof;

FIG. 7 is a rear view thereof;

FIG. 8 is a front view thereof;

FIG. 9 is a left side view thereof; and,

FIG. 10 is a right side view thereof.

The alternating short and long dash lines in all views represent the boundaries of the claim, and the dash lines in FIGS. 5-10 are included for the purpose of illustrating unclaimed portions of the reagent card. None of the broken lines form a part of the claimed designed.
